ABSTRACT: The invention disclosed herein is a smoke suppressant additive comprising an ether, a Group IIA metal carboxylate and a Group IIB metal carboxylate. A preferred fuel additive is a mixture of an alkyl ether of ethylene glycol and barium and zinc alkanoates wherein the weight ratio of ether to total carboxylates is from about 4:1 to 1:1. A further improved additive is obtained when a Group IIA metal sulfonate, especially a barium alkaryl sulfonate, is incorporated into the carboxylates-ether additive mix. An additive mixture having a ratio of about 1 to 2 parts ether and 1 to 2 parts of barium alkaryl sulfonate per part barium and zinc alkanoates, is particularly suitable.

SMOKE SUPPRESSANT COMPOSITIONS FOR
PETROLEUM FUELS

CROSS-REFERENCES TO RELATED APPLICATIONS

This application is a continuation-in-part of my copending application, Ser. No. 694,819 filed Jan. 2, 1968.

BACKGROUND OF THE INVENTION

This invention relates to new fuel additives. In particular, it relates to new fuel additives which reduce the smoke and soot formed during the operation of internal combustion engines, especially compression ignition engines.

The petroleum industry has encountered serious problems in supplying the demand for middle distillate and heavy residual fuel oils suitable for injecting into compression ignition engines, which will not contribute materially to the pollution of the atmosphere through smoke and soot production. Coupled with this specific need for a diesel fuel mixture with reduced smoking characteristics, there is also an urgent need for liquid hydrocarbon fuel mixtures having improved combustion characteristics for spark ignition and jet engines.

Attempts have been made to reduce the visible, black smoke and soot present in exhaust emissions formed during the oxidation of liquid hydrocarbon fuels. By way of example, certain metallic smoke suppressant mixtures have been employed in compression ignition engines, but objections to these mixtures are that they leave deposits in engine crankcases as a result of blowby from cylinders, can be expensive to produce and package, and can form undesirable combustion products in proportion to their content of metal. Further it has been additionally proposed to incorporate various materials into fuels to inhibit their soot, sludge and clogging tendencies. However, some of these materials have proven susceptible to emulsification upon storage and, in certain cases have shown a tendency to lower the Cetane Number of diesel fuels, or reduce the Octane Number of gasoline, while others have reduced the stability of fuel to oxidation during storage. Further, these and other additives have not generally imparted other beneficial properties to fuels, such as corrosion protection for engine surfaces, or surfactant properties to help cleanse injectors in diesel engines and provide a more uniform spray pattern therein in addition to smoke and soot suppressing action.

Accordingly there exists an urgent need to produce a multifunctional hydrocarbon fuel additive, capable of suppressing smoke and soot formed by operating internal combustion engines and otherwise improving combustion, free of the side effects and deficiencies of the prior art.

SUMMARY OF THE INVENTION

It is an object of this invention to provide a liquid hydrocarbon fuel additive and, in particular, a diesel fuel additive which can reduce the visible black smoke and soot formed during operation of internal combustion engines.

It is an object of this invention to provide a smoke and soot suppressing fuel additive which produces a minimum of ash upon combustion.

It is a further object of this invention to provide a smoke suppressant fuel additive which imparts improved oxygen stability to a base fuel.

It is an additional object of this invention to provide a fuel additive, which when mixed with a fuel, does not adversely effect Cetane Number and water tolerance characteristics of the base fuel, yet which reduces visible smoke and soot formed during combustion of the fuel.

It is another object of this invention to provide a fuel additive which imparts corrosion inhibiting tendencies to fuel mixtures thereof toward copper and carbon-steel engine surfaces, such inhibition being important during fuel storage, fuel transport, and actual engine use.

It is also an additional object of this invention to provide an additive, which acts to promote more uniform spray patterns and assists in cleansing injectors in diesel engines.

Other aspects, objects and advantages of this invention will be evident to those skilled in the art in view of this disclosure.

The above and other objects of this invention are met by a fuel additive comprising an ether, a Group IIA metal salt of an organic acid, and a Group IIB metal salt of an organic acid. Additive combinations of barium and zinc salts of alkanoic acids branched in the alpha position, and glycol ethers, particularly alkyl ethers of ethylene glycol, impart particularly significant reduced smoke and soot forming properties to fuels. An especially effective additive is a mixture of the monomethyl ether of ethylene glycol and of barium- and zinc-2-ethylhexanoates, wherein the weight ratio of barium to zinc metal is about 10 to 1 and the weight ratio of ether to carboxylates is from about 2:1 to 1.5:1.

Fuel additives having further improved smoke suppressant characteristics are obtained when the aforesaid carboxylates-ether mixtures also have incorporated therein a Group IIA metal sulfonate, particularly a barium alkaryl sulfonate. A particularly preferred additive is a mixture of 1-methoxy-2-propanol, a barium alkaryl sulfonate having a Molecular Weight of about 1000, barium 2-ethylhexanoate, and zinc-2-ethylhexanoate.

A fuel mixture having reduced soot and smoking characteristics is formed when the aforesaid carboxylates, ether and sulfonate mixtures are dispersed or dissolved in liquid hydrocarbon fuels. A preferred fuel mixture is a diesel fuel containing from about 0.2 to 0.5 percent by weight barium alkaryl sulfonate, from about 0.1 to 0.6 percent by weight barium and zinc 2-ethylhexanoates and from about 0.2 to 0.5 percent by weight 1-methoxy-2-propanol.

Further, according to the invention there is provided a method for operating an internal combustion engine which comprises passing a liquid hydrocarbon fuel mixture containing an additive of this invention through the fuel supply system to the combustion chamber of said engine, and causing ignition of the fuel therein in normal fashion. This method of operation is particularly effective in operating a compression ignition engine utilizing the unique fuel additives.

In general, the Group IIA and Group IIB metals may be combined with any organic acids to form the salts employed in this invention. Such salts can be aliphatic or aromatic carboxylates, e.g. alkyl, aryl, alkaryl, alkenyl, alkynyl, aralkyl or alicyclic. Some specific examples of acids are: methacrylic, ethanoic, propanoic, butanoic, 2-ethylhexanoic, decanoic, eicosanoic, tricontanoic, benzoic, naphthoic, 2-phenylethanoic, 3-propylbenzoic, cyclobutanoic, cyclodecanoic, glycolic, propynoic, fumaric, and the like. It is to be understood that in each case the acid anion of Group IIA metal salt may be identical to or different from the acid anion of the Group IIB metal salt. Further, a mixed (unsymmetric) salt of a Group IIA and/or Group IIB metal may be employed. The Group IIA and/or Group IIB metal mixed (unsymmetrical) salts are employed, for example, together with symmetric salts or unsymmetric salts of similar or dissimilar Group IIA and/or Group IIB metals.

Some specific salts which may be combined with ethers to form smoke suppressant mixtures include: barium and cadmium 2-ethylhexanoates; strontium decanoate and cadmium 3-methylnonanoate; barium and cadmium o-propylbenzoates; calcium and cadmium cyclobutanoates; magnesium methylcycloheptanoate and zinc 2-ethylpentanoate; strontium hexanoate and mercury 2ethylbutanoate; strontium hexanoate and mercury 2-ethylbutanoate; beryllium and zinc oleates or linoleates; and barium fumarate and zinc octanoate. Some specific mixed salt combinations include: barium 2-ethylhexanoate 2,2-dimethylpropanoate and zinc 2-methyldecanoate; barium methacrylate pentanoate and cadmium glycolate tridecanoate.

The ethers employed in the present invention are, in general, those having the following structural formulas: $R(O-R')_nOR''$ wherein n is an integer preferably between about 0 to 10; R is a hydrocarbyl radical, R'' is hydrogen or hydrocarbyl such that, when n is a whole integer, R'' is hydrogen or

hydrocarbyl, and when n is zero, R'' is hydrocarbyl, and R' is a hydrocarbylene radical, such as methylene, ethylene or the like, and the total number of carbon atoms in a molecule is preferably less than about 30; and

wherein n' is an integer preferably having the value of 1 or 2, and R' and R''' are hydrocarbylene radicals and the molecule preferably contains less than about 30 carbon atoms.

Thus, when R and R'' are hydrocarbyl radicals, typical groups include, for instance: alkyl, alkenyl, aryl, alkaryl, aralkyl, or alicyclic radicals. Examples of suitable hydrocarbyl radicals are: methyl, ethyl, propyl, butyl, 2-ethylhexyl, neodecyl, dodecyl, octadecyl, eicosyl, nonacosyl, phenyl, naphthyl, benzyl, tolyl, ethylphenyl, phenylhexyl, propylphenyl, cyclohexyl, cyclopropyl, cyclopentyl, butenyl, octenyl, linoleyl, etc.

When R' and R''' are hydrocarbylene radicals, typical groups include, for example: alkylene, arylene, alkarylene, aralkylene, alkenylene or alicylene radicals. Suitable hydrocarbylene radicals are: methylene, ethylene, propylene, isohexylene, decylene, phenylene, cyclohexylene, pentenylene, etc.

Examples of simple ethers useful in this invention are: diethyl ether, isopropyl ether, methyltert-butyl ether, ethylbutyl ether, decyl butyl ether, nonacosyl methyl ether, allyl ethyl ether, vinyl isopropyl ether, cyclopropyl methyl ether, dicyclobutyl ether, methyl ethyl ether, benzyl methyl ether, benzyl ethyl ether, diphenyl ether, anisole, bis(2-chloroisopropyl) ether, and the like.

Examples of heterocyclic ethers useful in this invention are: such heterocyclic monoethers as tetrahydrofuran, ethylene oxide, propylene oxide, furan; such heterocyclic diethers as para-dioxane; meta-dioxane; dioxolane; 2-(3-heptyl) 1,3-dioxolane; 2-(3-heptyl) 1,3-dioxan-5-ol; 2-(3-heptyl) 1,3-dioxolane-4-methanol; and such heterocyclic triethers as symtrioxane; ethyltrioxane; and the like.

DESCRIPTION OF PREFERRED EMBODIMENTS

Enhanced reduction of smoke and soot from fuel combustion is obtained when barium and zinc salts of organic acids are employed.

Low Molecular Weight alcanoic acids, and especially alcanoic acids having from about four to 12 carbon atoms, are particularly preferred. The acids employed are preferably soluble in fuels.

Generally the alcanoic acyclic acids tend to leave fewer deposits on combustion and oxidize more readily than unsaturated or cyclic acids, and accordingly are preferred.

Further improvement in smoke suppression is obtained when the Group IIA and Group IIB salts of organic acids, especially alcanoic acids having from four to 12 carbon atoms, and particularly the barium and zinc salts thereof, are branched in the alpha position.

Examples of suitable salts include those formed by combining any of the Group IIA and Group IIB metals with any of the acids set forth in the following table to form symmetrical or unsymmetrical salts:

Group IIA	Group IIB	Acid
Barium	Zinc	2-Methylpropanoic acid
Strontium	Cadmium	3-Methylbutanoic acid
Calcium	Mercury	2-Methylpentanoic acid
Magnesium		2,2-Dimethylhexanoic acid
Beryllium		2-Ethyloctanoic acid
		2-Propylnonanoic acid
		2-Methylundecanoic acid
		2,2-Diethylheptanoic acid
		2,2-Dimethyldecanoic acid

An especially preferred salt additive is the combination of Group IIA and Group IIB salts of 2-ethylhexanoic acid, and particularly, of barium and zinc 2-ethylhexanoates and of barium and cadmium 2-ethylhexanoates.

It is to be recognized that the di and poly carboxylic homologs of those monocarboxylates already described may be substituted therefor. Examples of such homologs include: barium and zinc adipates; strontium and zinc octadecanedioates; barium and cadmium pimelates; and the like.

Group IIA salts of carboxylic acids can be prepared for example, by reacting 2 moles carboxylic acid with 1 mole powdered dry Group IIA metal hydroxide in hydrocarbon or petroleum solvent, and raising the temperature above 100°C. to drive off the water formed. A composite of Group IIA and Group IIB salts of carboxylic acids can be prepared, for example, in one reaction step, by similarly reacting 2 moles of one or more carboxylic acids with $(1-x)$ mole dry Group IIA hydroxide and x mole dry Group IIB hydroxide, where x is stoichiometrically calculated to supply a desired weight percent Group IIB metal in the product. The metal carboxylate products are usually solids, but are preferably used as a clear solution in a petroleum solvent. Solubility of salts in petroleum solvent can be increased by heating, addition of small quantity of oxygenated coordinating solubilizer, and/or use of ultrasonics.

Further, it will be recognized that derivatives of the aforementioned metal carboxylates having groups, preferably polar, substituted in place of hydrogen may also be incorporated into hydrocarbon fuels. Such substituents must be essentially nonreactive to the fuel and include, for example, such polar groups as halogen, amino, nitro, nitrate, hydroxyl, and the like.

Generally the preferred ethers are those normally liquid mono or di ethers of polyols soluble in fuel. Examples of these ethers are: monomethyl ether of diethylene glycol, monoethyl ether of diethylene glycol, dimethyl ether of propylene glycol, monoethyl ether of triethylene glycol, diethyl ether of dipropylene glycol and alkylphenoxy polyethoxyethanols, and the like. Alkyl ethers of polyoxyalkylene glycols, said glycol ethers having from about three to 10 carbon atoms, are particularly preferred.

Especially suitable ethers are the monoalkyl ethers of glycols and in particular, of ethylene glycol such as: monoethyl ether of ethylene glycol, monopentyl ether of ethylene glycol, mono(2-ethylbutyl) ether of ethylene glycol, monopropyl ether of ethylene glycol, and monopropyl ether of propylene glycol; and the diethers of glycols and, particularly, of ethylene glycol, such as dibutyl ether of ethylene glycol.

Ethers producing unusually good soot and smoke reduction in fuels in conjunction with the carboxylates of this invention are the monomethyl ether of ethylene glycol and 1-methoxy-2-propanol.

Additionally, fuel mixtures of dialkyl ethers of ethylene glycol, and particularly of dimethyl ether of ethylene glycol, commonly called glyme, exhibit improved Cetane Numbers, as compared to diesel fuels without said ethers, as well as effective soot and smoke reductions. This improvement is also seen in such dialkyl ethers of polyalkylene glycols as dimethyl ether of triethylene glycol. Accordingly, such ethers comprise another particularly preferred class of ethers.

It will be recognized that the derivatives of the aforementioned ethers having groups, preferably polar, substituted in place of hydrogen may also be incorporated into fuels. Such substituents must be essentially nonreactive to fuel and include such polar groups as halogen, amino, nitro, nitrate, hydroxyl, and the like.

Typical fuel additives of this invention employed in internal combustion engines include those formed by combining any

Group IIA carboxylate and any Group IIB carboxylate, with any ether as set forth below.

calcium o-propylbenzenesulfonate;
magnesium cyclooctanesulfonate;

Group IIA salt	Group IIB salt	Ether
Beryllium Isobutanoate	Mercury 2-ethylpentanoate	Diethyl ether.
Barium 2-ethyldecanoate	Zinc 2,2-dimethyloctanoate	Hexyl pentyl ether.
Strontium linoleate	Cadmium 2-heptenoate	Dipropyl ether of propylene glycol.
Barium 3-methyltetradecanoate 2,3-diethylundecanoate	Zinc 2,4-dibutylbenzoate	Methyl ethyl ether of ethylene glycol.
Magnesium 2-phenylethanate	Zinc 3-phenyldecanoate 2-ethylnonanoate	Monooethyl ether of decylene glycol.
Calcium cyclopentanoate	Cadmium cyclobutanoate	Dibenzyl ether.
Barium 2-methylbenzoate	Mercury 3-propylbenzoate	Benzyl ethyl ether.

Preferred fuel additives of this invention include additives 15 1-6, the latter three being especially preferred.

1. Barium 2-methylpropanoate
Zinc 2-methylpropanoate
Monomethyl ether of propylene glycol
2. Barium 2-ethylbutanoate
Zinc 2-ethyloctanoate
Diethyl ether of pentylene glycol
3. Barium 2-methylundecanoate 2-ethylpropanoate
Zinc 2-methylundecanoate
Monomethyl ether of triethylene glycol
4. Barium 2-ethylhexanoate
Zinc 2-ethylhexanoate
Monomethyl ether of ethylene glycol
5. Barium 2-ethylhexanoate
Zinc 2-ethylhexanoate
Dimethyl ether of ethylene glycol
6. Barium 2-ethylhexanoate
Zinc 2-ethylhexanoate
1-Methoxy-2-propanol

In a preferred embodiment of this invention, a Group IIA metal sulfonate is incorporated in the aforesaid carboxylates- 35 ether additive mixes.

The sulfonic acids from which the sulfonates employed in the present invention are formed are those having the following structural formula:

where R is a hydrocarbyl radical.

R may be an alkyl, alkenyl, aryl, alkaryl, alkynyl, aralkyl or alicyclic radical. Examples of suitable R groups are: methyl, propyl, 2-ethylhexyl, neodecyl, dodecyl, octadecyl, eicosyl, 45 pentacosyl, phenyl, naphthyl, benzyl, tolyl, ethylphenyl, phenylhexyl, cyclohexyl, cyclopropyl, butenyl, linoleyl, propynyl, hexynyl, and the like.

Examples of sulfonic acids employed as sulfonates are: methanesulfonic acid, decanesulfonic acid, 2-ethylhexanesulfonic acid, pentanesulfonic acid, phenylmethanesulfonic acid, decylbenzenesulfonic acid, naphthalenesulfonic acid, octenesulfonic acid, cyclohexanesulfonic acid, and the like, and mixtures thereof. Further, mixed (unsymmetric) sulfonates may be employed to raise or lower the metal content, as 55 desired.

Some specific sulfonates useful in this invention include:
barium nonanesulfonate;

strontium 2-ethylheptanesulfonate;

- 15 beryllium oleylsulfonate;
barium 2,2-dimethylundecanesulfonate;
barium hexanesulfonate p-toluenesulfonate;
calcium naphthalene-1,6-disulfonate;
and mixtures thereof.
- 20 Enhanced smoke suppressant characteristics are obtained when barium sulfonates are employed.
Generally it is preferred that fuel-soluble sulfonates be used, such as high Molecular Weight petroleum sulfonates, including "mahogany" acid sulfonates.
- 25 Naturally occurring alkaryl hydrocarbons, such as those found in mixed kerosene fraction of petroleum, may be employed as the hydrocarbyl substituents of the sulfonic acids. The sulfonic acids may be made according to the processes disclosed in U.S. Pat. No. 2,395,713 and U.S. Pat. No. 30 2,388,677 and refined according to U.S. Pat. No. 2,387,866.

Synthetically produced mixed alkaryl sulfonates of Group IIA metals, especially barium having two alkyl groups per aromatic group are well suited. It is particularly preferred that each alkyl group of the mixed sulfonates is a linear group of from about 14 to 18 carbon atoms, said sulfonate having a Molecular Weight of from 800 to 1,500, preferably from 900 to 1,100.

Examples of preferred sulfonates include:
barium 2-hexadecyl-3-heptadecylbenzenesulfonate;
40 barium 2-(3-methylpentadecyl)-6-octadecylbenzenesulfonate;
barium 2-octadecyl-8-(2-ethylhexadecyl) naphthalenesulfonate;
barium 2-ethyltetradecyl-8-(3-methyltetradecyl) naphthalenesulfonate;
and mixtures thereof and especially those having a Molecular Weight of about 1,000.

Further, it will be recognized that derivatives of the aforementioned sulfonates having groups, preferably polar, substituted in place of hydrogen may also be incorporated into hydrocarbon fuels. Such substituents must be essentially non-reactive to the fuel and include, for example, such polar groups as halogen, amino, nitro, nitrate, hydroxyl, and the like.

Typical additive mixtures of this embodiment of the invention employed in fuels include those formed by combining any Group IIA carboxylate, any Group IIB carboxylate, any ether and any Group IIA sulfonate set forth below.

Group IIA salt	Group IIB salt	Ether	Group IIA sulfonate
Beryllium 2-methylpropanoate	Mercury 2-ethylpentanoate	Diethyl ether	Barium tridecanesulfonate.
Barium 2-ethyldecanoate	Zinc 2,2-dimethyloctanoate	Hexyl pentyl ether	Strontium hexadecylbenzenesulfonate.
Strontium linoleate undecanoate	Cadmium 2-heptenoate	Dipropyl ether of propylene glycol	Calcium cyclohexanesulfonate.
Magnesium phenylethanate	Zinc 2-phenyldecanoate	Monooethyl ether of decylene glycol	Magnesium decenesulfonate.
Calcium cyclopentanoate	Cadmium cyclobutanoate	Dibenzyl ether	Beryllium naphthylpropanesulfonate.
Barium 2-methylbenzoate	Mercury 2-propylbenzoate	Benzyl ethyl ether	Barium nonadecanesulfonate.
		Monophenyl ether of ethylene glycol	

Preferred mixtures of the invention containing sulfonates includes additives 1-6, the latter three being especially preferred.

1. Barium 2-methylpropanoate
Zinc 2-methylpropanoate
Monomethyl ether of propylene glycol
2. Barium 2-ethylbutanoate
Zinc 2-ethyloctoate
Diethyl ether of pentylene glycol
Barium 1,2,3-tridodecylnaphthalenesulfonate
3. Barium 2-methylundecanoate
Zinc 2-methylundecanoate
Monomethyl ether of triethylene glycol
Barium 2-octadecylanthracenesulfonate
4. Barium 2-ethylhexanoate
Zinc 2-ethylhexanoate
Monomethyl ether of ethylene glycol
Barium 2-undecyl-3-dodecylbenzenesulfonate
5. Barium 2-ethylhexanoate
Zinc 2-ethylhexanoate
Dimethyl ether of ethylene glycol
Barium 2-heptadecyl-8-decylnaphthalenesulfonate
6. Barium 2-ethylhexanoate
Zinc 2-ethylhexanoate
Dimethyl ether of diethylene glycol
Barium 2-tridecyl-4-pentadecylbenzenesulfonate

Generally, the weight proportions of ether to carboxylates in the additives of this invention may vary between wide limits. It is preferred that the weight ratio of ether to the total combined weight of Group IIA and Group IIB carboxylates is between about four parts to 1.0 parts ether per part carboxylates. In the case of the barium and zinc alkanoates and glycol ether additive mixtures, the weight ratio of ether to the combined weight of barium and zinc alkanoates is preferably between about three to 1.5 parts ether per part carboxylates.

In the case of the especially preferred additive mixtures of barium and zinc 2-ethylhexanoates, and monomethyl ether of ethylene glycol, it has been found that best results are obtained when the weight ratio of ether to the total weight of barium and zinc carboxylates is from about 2.0 to 1.5 parts ether per part carboxylates.

A synergistic effect resulting in improved smoke and soot reduction is observed when the proportion of Group IIA metal carboxylate is greater than the proportion of Group IIB metal carboxylate. This effect is especially evident where the Group IIA carboxylate is a barium salt and the Group IIB carboxylate is a zinc salt. Further reductions are noticed when the ratio of Group IIA metal to Group IIB metal (in the carboxylates) and especially of barium metal to zinc is from about 5:1 to 30:1 and particularly, from about 8:1 to 12:1 by weight. For best results it is especially preferred that the weight ratio be about 10 parts barium per part zinc.

A synergistic effect is also seen between the ether and the aforementioned carboxylate mixtures. This effect is particularly evident when alkyl glycol ethers, particularly the mono and dialkyl ethers of ethylene glycol, and especially the monomethyl ether of ethylene glycol, are employed.

Generally the sulfonates are employed in the carboxylates and ether additives of this invention to provide additional smoke suppressant improvement in the aforesaid salts and ether mixtures and to enhance the beneficial features of the additives, such as the detergency effects, and the anticorrosion effects.

For these and other purposes, generally the weight proportion of carboxylates and ether to sulfonates in the additives is from about one to three parts carboxylates and from about one to two parts ether per one to two parts sulfonate, and preferably from about one to two parts ether and one to two parts sulfonate per part total carboxylates.

In the case of the especially preferred additive of barium and zinc 2-ethylhexanoates, 1-methoxy-2-propanol and the barium alkaryl sulfonate having a Molecular Weight of about 1000, it has been found that best results are obtained when the weight ratio of additive components is about 1.4 parts ether and 1.4 parts sulfonate per part barium and zinc carboxylates.

Generally, the additive mixtures are employed in amounts which produce a significant reduction in the smoke and soot characteristics of hydrocarbon fuel. For this purpose, generally at least about 0.05 percent by weight of additive mixture should be utilized. Although amounts in excess of about 5 percent by weight may be employed, practical smoke and soot reductions are usually achieved with lesser amounts.

Usually, enhanced smoke reductions are achieved when the total concentration of Group IIA metal present as a carboxylate salt and, if present, as a sulfonate, in the fuel mixture is from 0.04 to 0.08 percent by weight, preferably about 0.07 percent by weight.

Generally, the mixtures of Group IIA and Group IIB salts of this invention are employed in amounts which produce effective smoke and soot suppression. For this purpose, a minor amount of salts, usually a total of at least 0.05 percent by weight should be employed. Although greater amounts may be employed, generally it is not necessary to use more than about 5 percent by weight.

For best results it is preferred that the salts be employed in a total concentration of about from 0.1 to 2 percent by weight.

In the case of the especially preferred diesel fuel mixture of barium-and-zinc-2-ethylhexanoates it has been found that best results are obtained when a total of from about 0.1 to 0.6 percent by weight of salts are employed.

Basically the ethers are employed in amounts necessary to produce a significant reduction in the smoke and soot characteristics of the fuel mixture. For this purpose, generally at least 0.05 percent by weight of ether should be utilized. Although amounts in excess of about 5 percent by weight may be employed, practical smoke and soot reductions are usually achieved with lesser amounts. Best results are attained when the ethers are employed in concentration from about 0.1 to 1 percent by weight.

In the case of the particularly preferred diesel fuel mixtures of barium-and-zinc-2-ethylhexanoates and glycol ethers, it has been found that best results are obtained when from about 0.2 to 0.5 percent by weight of ether is employed, and from about 0.1 to 0.6 percent by weight of salts are employed.

The weight percentages of additives are based upon the weight of additive as compared to the total weight of the fuel mixture.

In order to reduce the amount of visible black soot and smoke emitted from internal combustion engines significantly, the Group IIA metal sulfonates are employed in minor amounts, at least at about 0.05 percent by weight. Generally no more than about 1 percent by weight of sulfonate based on the total weight of the fuel mixture, is employed. If greater amounts are employed no further substantial visible smoke and soot reductions are obtained.

For best results it is preferred that the Group IIA metal sulfonates, be employed in amounts from about 0.1 to 0.8 percent by weight based on the total weight of the fuel mixture.

In the case of the especially preferred diesel fuel mixtures of barium and zinc alkanoates and glycol ethers, best results are obtained when the sulfonates, especially barium alkaryl sulfonates, are employed in amounts from about 0.2 to 0.5 percent by weight, based on the total weight of the fuel mixture.

Generally, to form the novel carboxylates-ether mixtures the alkanoates are admixed with the ether by conventional means. If need be, a solubilizer may be added to the novel additive mixtures in amounts sufficient to form a homogeneous liquid concentrate with enhanced solubility in liquid hydrocarbon fuels.

To prepare fuel mixtures of the carboxylates, ether, and sulfonate additive mixes advantageously, one may initially dissolve or disperse the metal carboxylates in the fuel, then add the ether to the carboxylate-fuel mixture, and finally add the sulfonate to the fuel mixture. The additive mix may also be added directly to the fuel, or a solubilizer may be added to the additive mix and the resulting composition admixed with a fuel.

Generally, the aforesaid solubilizers are inert petroleum solvents, such as petroleum ether, a hydrocarbon fuel, Varsol, White Oil, alcohols, especially glycols, and the like, and mixtures thereof.

If a solubilizer is employed in the case of the salts, ether and sulfonate additives, it is preferred that the proportion of salts be between about 10 to 30 percent by weight, the ethers between 15 to 40 percent by weight, the sulfonates between 15 to 25 percent by weight, and the solvent between about 60 to 5 percent by weight, wherein said weight percentages are based upon the total weight of said salts, ether, sulfonate, and solvent.

In general, any liquid hydrocarbon fuel including heating fuels, and particularly those fuels useful in internal combustion engines can be employed as the fuel to which the novel additives may be added. It is preferred that the liquid hydrocarbon fuel be a diesel fuel having an initial boiling point of about 300° F. and an end distillation point of about 750° F. Diesel fuels having a boiling range of from about 400° F. to about 675° F. such as No. 2 diesel fuel are especially preferred.

The following examples are given to further illustrate the nature of the invention and are not limitative of scope.

EXAMPLE I

In order to demonstrate the smoke and soot suppressancy of the additives of this invention in hydrocarbon fuels, a diesel fuel mixture was prepared as follows: about 60 parts by weight of a liquid solution containing about 19 parts by weight barium 2-ethylhexanoate, about 3 parts by weight zinc 2-ethylhexanoate and about 38 parts inert petroleum solvent was admixed with about 40 parts of a designated glycol ether. The ratio of ether to salts was about 1.8 to 1. Selected quantities of

nected to a two-way valve of the smoke meter. Typical engine temperatures were:

Intake Air	—	150° F.
Gallery Oil	—	120°-140° F.
Coolant	—	212° F.

Firstly, the engine was warmed up on the base fuel at a condition wherein no visible black smoke was observed in the exhaust gases. The fuel flow was increased until the fuel flow was about 13 cubic centimeters per minute, corresponding to the appearance of visible black smoke in the exhaust gases and a Hartridge Smoke Number (HSN) reading of about 40.

The smoke suppressant fuel mixture of the invention was then substituted for the base fuel and the engine was run for about 5 minutes to allow stabilization. The smoke meter reading was then recorded. Next a mixture of a base fuel and 0.7 percent by weight of commercially available smoke suppressant was substituted in place of the additive mixture as a reference. After a 5-minute delay for engine stabilization, Smoke Meter readings were recorded. The cycle of base fuel, additive fuel, and reference fuel was repeated two additional times.

The following table illustrates the effectiveness of the novel additive mixtures. In the table, the Hartridge Smoke Number (HSN) values are given as the average of the three consecutive runs. The "Percent Effectiveness" is represented by the equation

$$\frac{[HSN_{base} - HSN_{additive}]}{[HSN_{base} - HSN_{reference}]} \times 100\%$$

and is a

measure of the efficiency of the novel fuel mixtures, as compared to a commercial smoke suppressant fuel mixture. The weight percent of additive is based on the weight of the component as compared to the total weight of the fuel mixture.

RESULT OF SMOKE SUPPRESSANT TESTS

Additive in base fuel	Weight percent of additive	HSN, base fuel	HSN, additive in base fuel	HSN, reference	Percent effectiveness
No. 1: Barium 2-ethylhexanoate.....	0.13				
Zinc 2-ethylhexanoate.....	0.01				
Monomethyl ether of ethylene glycol.....	0.26				
Total.....	0.40				
No. 2: Barium 2-ethylhexanoate.....	0.34				
Zinc 2-ethylhexanoate.....	0.03				
Monomethyl ether of ethylene glycol.....	0.50				
Total.....	0.87				
No. 3: Barium 2-ethylhexanoate.....	0.23	55	37	6	38
No. 4: Zinc 2-ethylhexanoate.....	0.39	67	65	10	3
No. 5: Monomethyl ether of ethylene glycol.....	0.50	42	38	8	12

this concentrate were mixed with a No. 2 diesel fuel described as follows.

The diesel fuel employed was a No. 2 diesel fuel containing 110 parts per million of a known antioxidant additive, such as a 1,1-dimethylalkylamine, used as color stabilizer and antioxidant during fuel storage. The No. 2 diesel fuel possessed the following characteristics:

1. Cetane Number, minimum	43
2. Flashpoint, ° F. minimum	140
3. Distillation, 90 percent recovered, ° F. maximum	600
4. Viscosity, centistokes at 100° F.	2.1-4.3
5. Carbon residue (10 percent bottoms)	0.25

The Smoke suppressants were evaluated in a single cylinder cetane type diesel engine equipped with a Hartridge Smoke Meter. An exhaust probe was inserted in the exhaust pipe about 4 feet from the exhaust manifold. The probe was con-

60 The value of 100 on the Hartridge Smoke Number Scale represents completely black smoke, 30 and below represents a clear exhaust acceptable under all running conditions. Use of zinc 2-ethylhexanoate as the only additive, at concentrations from 0 to 0.39 weight percent in base fuel, gave zero percent effectiveness in smoke reduction.

65 The results set forth in the preceding example demonstrate the effectiveness of fuels containing barium and zinc 2-ethylhexanoates, and glycol ethers in reducing smoke and soot formation. The results also demonstrate the synergistic interaction between the barium and zinc salts which is especially evident when the ratio of barium to zinc metal is about 10 to 1. Similar results are obtained when other combinations of Group IIA and Group IIB metal salts are substituted for the barium and zinc salts in the above example.

70 Thus when the salts formed by the combination of Group IIA metals, Group IIB metals and the acids listed below are

substituted for the barium and zinc 2-ethylhexanoate employed in example I satisfactory results are obtained.

Group IIA	Group IIB	Acids
Strontium	Zinc	Octanoic acid
Calcium	Cadmium	Cyclopentanoic acid
Magnesium	Mercury	2-Propylbenzoic acid
Beryllium		2-Propylhexanoic acid
Barium		2,2-Dimethyloctanoic acid

The results of the preceding example also demonstrate the effectiveness of fuel mixtures of alkyl ethers of ethylene glycol, and especially the monomethyl ether of ethylene glycol and of barium and zinc salts of low Molecular Weight alkanoic acids, particularly those acids branched in the alpha position, in reducing smoke and soot. Similar results are also obtained when other combinations of ethers and Group IIA and Group

ether as described in the first set of results tabulated in example I, were mixed with a No. 2 diesel fuel similar in characteristics to that described in example I.

The smoke suppressants were evaluated in a Cummins 5 C-175 engine, naturally aspirated, and equipped with Hartridge Smoke Meter. In testing, the engine was warmed up with base (untreated) fuel and the fuel throttle was adjusted to give about 140 Brake Horsepower (BHP), and Hartridge Smoke Meter readings were noted. Next the fuel throttle was 10 opened slightly to give about 150 BHP and thereafter to give about 155 BHP. At both these loads, smoke meter readings were noted.

Next, a smoke suppressant fuel mixture of the invention was 15 substituted for the base fuel and smoke meter readings were taken at the three engine power levels previously employed.

The following table illustrates the effectiveness of the novel additive mixtures.

RESULTS OF SMOKE SUPPRESSANT TESTS

Additive in base fuel	Weight percent of additive	Brake-horse power	HSN, base fuel	HSN, additive in base fuel	Percent reduction in smoke
No. 1:					
Barium 2-ethylhexanoate-----	0.13	140	26	17	35
Zinc 2-ethylhexanoate-----	0.01	150	37	22	40
1-methoxy-2-propanol-----	0.26	155	52	31	40
Total-----	0.40				
No. 2:					
Barium 2-ethylhexanoate-----	0.064	140	30	25	17
Zinc 2-ethylhexanoate-----	0.006	150	37	32	14
1-Methoxy-2-propanol-----	0.130	155	50	43	14
Total-----	0.200				

The reduction in smoke is represented by:

IIB metal salts of organic acids are substituted for the salts and ethers in the above example. Satisfactory results are obtained when other ethers such as methyl ethyl ether, diethyl ether of diethylene glycol, dioxane, and dibenzyl ether are substituted for the monomethyl ether of ethylene glycol.

It should be noted that the components of the fuel mixtures of this example, when tested individually in diesel fuel, showed much less effectiveness in reducing soot and smoke than the combination thereof. This demonstrates that multiple synergism is obtained when the metal salt-fuel mixtures have ethers additionally incorporated.

When other liquid hydrocarbon fuels, such as jet fuel, heating fuel, gasoline, etc., are substituted for the diesel fuel tested, the smoke and soot forming properties of these fuels are beneficially improved.

EXAMPLE II

In order to further demonstrate the smoke and soot suppressancy of hydrocarbon fuel mixtures of the additives of this invention, a diesel fuel mixture was prepared according to the procedure followed in example I. Selected quantities of a concentrate, having the same proportions of carboxylates and

35

EXAMPLE III

In order to evaluate the smoke suppressant effectiveness of the carboxylates, ether and sulfonate additive mixtures of this invention, selected quantities of barium and zinc 2-ethylhexanoate, the monomethyl ether of ethylene glycol and a synthetic barium alkaryl sulfonate (14.6 percent Ba metal) with a Molecular Weight of about 1000 were individually dissolved in the No. 2 diesel fuel of example I to form a fuel mixture. The fuel mixture was tested by the same procedure as 40 described in example I. The mixture had a weight ratio of additive components of about 1.4 parts ether to 1.4 parts sulfonate per part carboxylates. The weight ratio of the barium carboxylate to the zinc carboxylate was about 10 to 1. The barium and zinc carboxylates component of the additive was 45 added to the fuel as a liquid, the composition of the liquid being about 37 parts by weight carboxylates to 63 parts by weight inert petroleum solvent. The reference standard of example I was also tested for comparing soot and smoke reductions.

50 The following table illustrates the effectiveness of this aspect of the invention.

RESULTS OF SMOKE SUPPRESSANT TESTS

Component in base fuel	Weight percent	HSN, base fuel	HSN, additive in base fuel	Test results	
				HSN, reference	Percent effectiveness
No. 1:					
Barium 2-ethylhexanoate-----	0.11				
Zinc 2-ethylhexanoate-----	0.01				
Monomethyl ether of ethylene glycol-----	0.17				
Barium dialkaryl sulfonate-----	0.17				
Total-----	0.46				
No. 2:					
Barium 2-ethylhexanoate-----	0.16				
Zinc 2-ethylhexanoate-----	0.02				
Monomethyl ether of ethylene glycol-----	0.25				
Barium dialkaryl sulfonate-----	0.25				
Total-----	0.68				
No. 3:					
Barium 2-ethylhexanoate-----	0.16				
Zinc 2-ethylhexanoate-----	0.02				
Monomethyl ether of ethylene glycol-----	0.50				
Total-----	0.68				

The results of the preceding example demonstrate the effectiveness of the carboxylates, ether and sulfonate additive mixtures, particularly of the barium and zinc alkanoates, glycol ethers, and barium alkaryl sulfonates, as smoke and soot suppressants for fuels. Similar results are obtained when other combinations of Group IIA and Group IIB metal salts of organic acids, ethers, and Group IIA metal sulfonates are substituted for the components in the above example.

The smoke and soot reductions achieved in fuels by employing salts, ether, and sulfonate additives are demonstrated by comparing the unexpectedly increased effectiveness of additive 02, as contrasted to additive 03, in this example, wherein a portion of the ether of additive 03 was replaced by a Group IIA metal sulfonate.

EXAMPLE IV

To further illustrate the novel carboxylates, ether and sulfonate smoke and soot suppressant additive mixes of this invention, mixtures having the same components and proportions of batch #1 in example III, with the exception that 1-methoxy-2-propanol was substituted for the monomethyl ether of ethylene glycol, were prepared and selected quantities were added to the No. 2 fuel described below.

The No. 2 diesel fuel possessed the following characteristics:

1. Cetane Number	51
2. Distillation, 10 percent point, °F.	414
90 percent point, °F.	562
3. Total sulfur	0.072
4. Gravity, °API at 60° F.	36.9
5. FIA	
Aromatics, %	25
Olefins, %	0
Saturates, %	75

The Smoke Suppressants were evaluated under simulated conditions of constant speed in a Cummins NH-220, naturally aspirated, six cylinder four cycle engine mounted in a 1965 International Harvester DC OF-405 cab-over tandem-drive axle truck tractor.

To simulate actual driving conditions the tractor was mounted on a modified Clayton Chassis dynamometer, capa-

ble of simulating the inertia produced by the motion of the truck tractor under actual driving conditions.

In order to measure the smoke and soot produced during operation of the engines, a light extinction full-flow smokemeter employed by the United States Public Health Service was mounted directly on the exhaust stack of the truck tractor.

The smokemeter was mounted 5.5 inches above the exhaust pipe so that a light source mounted at one end of a collimating tube would project a beam of light directly through the exhaust plume. A photoelectric collector cell mounted on the other end of the collimating tube measured the light passing through the exhaust plume, and the percent transmittance was then recorded. Generally, a rating of 20 percent opacity (or light obscuration) corresponds to a Ringlemann Number of 1.

The Cummins HN-220 engine and tractor were operated at simulated constant speed conditions corresponding to the following engine speed and vehicle speeds.

Operating Condition	Engine Speed, r.p.m.	Simulated Vehicle Speed, M.P.H.
A	1500	26
B	1700	29
C	1900	32
D	2100	35

In order to evaluate the effect of the smoke suppressant additives during operation of the truck trailers, the following procedure was employed.

The smokemeter was zeroed in with air to simulate a "no-smoke" condition. The engine was started and accelerated to seventh gear and operated at Operating Condition A. After 30 seconds, the smokemeter reading was taken. Then the speed was increased to that specified in Operating Condition B and after 30 seconds, the smokemeter reading was taken. This procedure was followed for Operating Conditions C and D. The entire cycle was repeated two additional times, and the results reported represent an average of three runs.

The reduction in smoke is represented by

$$\frac{[\text{Opacity}_{\text{base fuel}} - \text{Opacity}_{\text{additive}}]}{\text{Opacity}_{\text{base fuel}}} \times 100\%$$

Component in base fuel	Additive		Smoke tests at constant speed		
	Weight percent	Operating condition	Percent opacity, base fuel	Percent opacity, additive in base fuel	Percent smoke reduction
No. 1:					
Barium 2-ethylhexanoate	0.13	A	24	14	41

"Operating Condition" refers to the previous table showing vehicle simulated speed, and r.p.m.

For the light extinction smokemeter a reading of one hundred percent opacity equals total absorption of light and zero percent opacity equals 100 percent light transmittance.

In the diesel fuel mixtures illustrated, the concentration of Group IIA metal was about from 0.04 to 0.15 percent by weight and the concentration of the zinc metal was from 0.002 to 0.009 percent by weight of the fuel mixture.

Best smoke suppressancy was obtained when the barium concentration in the fuel was about 0.07 percent by weight.

The results of this example further demonstrate the effectiveness of the smoke and soot suppressant additives of this invention. Similar results are expected when the additives are employed in other hydrocarbon fuels as gasoline, jet fuel, and heating fuels.

EXAMPLE V

In order to test the tolerance of the novel fuel additive mixtures of this invention to water, selected quantities of the additives appearing in the table below were dissolved in 100 milliliters of the No. 2 diesel fuel, previously described in example I, and 10 milliliters of water were added. The diesel fuel mixtures were at room temperature when tested. The water and diesel fuel additive mixtures were shaken vigorously and allowed to settle. The mixtures were observed at periodic intervals for 10 days. The results of the test after 15 minutes are described in the table below.

Additive Component and weight % of Component in Base Fuel	Water Break at Oil Water Interface	Oil Phase
Barium 2-ethylhexanoate	0.13	Sharp
Zinc 2-ethylhexanoate	0.01	
Monomethyl ether of ethylene glycol	0.26	
Total	0.40	
Barium 2-ethylhexanoate		
Zinc 2-ethylhexanoate	0.12	Sharp
Monomethyl ether of ethylene glycol	0.17	
Barium alkaryl sulfonate	0.17	
Total	0.46	
Base fuel	Sharp	Clear

Upon standing for 10 days, no haze was observed in the oil phases.

EXAMPLE VI

In order to determine the effect of the new additives on the Cetane Number of diesel fuel, fuel mixture consisting of the No. 2 diesel fuel of example I in admixture with the additives of example V were tested against the No. 2 diesel fuel oil of example I. The Cetane Number of the No. 2 diesel fuel and novel fuel mixtures was determined by operating a single cylinder Cetane Test Engine in accordance with ASTM procedure D-613. The Cetane Number of the No. 2 base diesel fuel was about 43 while the Cetane Numbers of base fuel containing the aforementioned additives were also about 43. The results demonstrate that fuel mixtures of the novel additives do not adversely effect Cetane Number of the base fuel.

EXAMPLE VIII

In order to determine the relative stability of fuel additives of the invention under aging conditions involving air exposure and in order to evaluate the effectiveness of the additive in inhibiting residue formation and color degradation, the diesel fuel mixtures described in the previous example were subjected to the DuPont 300° F. Accelerated Fuel Oil Stability Test.

Fifty ml. of the diesel fuel mixtures were each aged in an oil bath held at 300° F. for 90 minutes. The samples were then filtered under vacuum (16" Hg) through a 4.25 cm. No. 1 Whatman Paper held in Millipore filter holder. The test tubes that held the aged samples were rinsed with 3 ml. portions of *n*-heptane; each wash being transferred to the filter holder. The filter holder and papers were washed with *n*-heptane under vacuum until free of fuel oil. The filters were air dried under vacuum and compared with reference standards. A fuel having a matching standard of No. 7 or lower is "passing." The results of the test showed that the base fuel had a Pad Rating of 7, while the base fuel-additive mixtures each had a rating of 3.

EXAMPLE VIII

In order to demonstrate the corrosion inhibition characteristics toward copper, which the smoke suppressant additives impart to fuels, particularly diesel fuel, the additives of example V were admixed with the diesel fuel of example I and tested according to ASTM procedure D-130. The ratings of the individual additive fuel mixture and base fuel were 1A.

EXAMPLE IX

To demonstrate the anticorrod effect of fuel mixtures containing the smoke suppressant additives of the invention on carbon steel under highly corrosive conditions, two-2-millimeter thick strips of carbon steel were separately immersed in the mixtures of the additives of example I in 400 milliliters (ml.) diesel fuel and 10 ml. of a 4 percent sodium chloride solution at a temperature of 100° F. The mixtures were stirred at 1000 r.p.m. and measurements were made at time intervals of the changes in voltage drop between the strips. Percent Corrosion was obtained from these measurements by means of previously obtained correlation between voltage drop versus Percent Corrosion measured for a carbon steel coupon tested under pipe line conditions. The following table describes the results of the test as noted after 24 hours immersion.

% Corrosion of Carbon Steel After 24 Hours		
01	Barium and zinc 2-ethylhexanoates	5.5
02	Monomethyl ether of ethylene glycol	
02	Barium and zinc 2-ethylhexanoates	0.0
03	Monomethyl ether of ethylene glycol	
03	Barium alkaryl sulfonate	
55	Base fuel (absence of antioxidant)	15.0

The results show the enhanced anticorrod properties of fuel mixtures of the smoke suppressants of the invention. The additives were present in the diesel fuel in a concentration of about 0.007 weight percent.

EXAMPLE X

To show the surfactant properties supplied to fuels by the smoke suppressants of this invention the additive-containing fuel blends of example V were tested in accordance with ASTM procedure D-971 to determine interfacial tension. Generally, the lower the tension, the greater is the surfactant property of the fuel. The table below illustrates the decrease in interfacial tension at 25° C., of diesel fuel mixtures versus distilled water.

Barium 2-ethylhexanoate	32.2
Zinc 2-ethylhexanoate	
Monomethyl ether of ethylene glycol	
02	
Barium 2-ethylhexanoate	26.5
Zinc 2-ethylhexanoate	
Monomethyl ether of ethylene glycol	
Barium alkaryl sulfonate	
03	
Base fuel	36.6

If desired, the fuel compositions of this invention may additionally contain oxidation inhibitors, corrosion inhibitors, antifoam agents, other smoke suppressants, sludge inhibitors, color stabilizers, and other additional agents adapted to improve the fuels in one or more respects. Further, other detergents, such as metal salts of monoesters of sulfuric acid formed from *n*-aliphatic alcohols containing from eight to 18 carbons, metal salts of di(2-ethyl-hexyl) sulfosuccinic acid, and especially Group IIA salts, particularly barium salts, and mixtures thereof may be additionally incorporated to the additives.

It will be understood that the specific embodiments set forth hereinabove are illustrative only and that the invention is not to be limited except as set forth in the following claims.

Therefore, I claim:

1. A smoke suppressant composition suitable for use in liquid hydrocarbon fuels comprising a Group IIA and Group IIB metal salt of an alcanoic acid branched in the alpha position, a Group IIB metal salt of an alcanoic acid branched in the alpha position, a group IIB metal salt of an alcanoic acid branched in the alpha position, an alkyl ether of a glycol having about three to 10 carbon atoms and a Group IIA metal sulfonate, wherein the weight ratio of Group IIA metal to Group IIB metal in the alkanoates is from about 5 to 1 to about 30 to 1 and the weight proportions of total alkanoates and ether to sulfonate is about 1 to 3 parts of total alkanoates and about 1 to 2 parts of ether to 1 to 2 parts of sulfonate.

2. The composition of claim 1 wherein the Group IIA metal salt is a barium salt, the Group IIB metal salt is a zinc salt, and the Group IIA metal sulfonate is a barium hydrocarbyl sulfonate.

3. The composition of claim 2 wherein the weight ratio of barium to zinc in the alkanoates is from about 8:1 to 12:1.

4. The composition of claim 3 wherein the alkanoates each have from about four to 12 carbon atoms, and the sulfonate is a barium alkaryl sulfonate.

5. The composition of claim 3 wherein the Group IIA metal salt is barium 2-ethylhexanoate, the Group IIB metal salt is zinc 2ethylhexanoate, the ether is 1-methoxy-2-propanol, the sulfonate is a barium alkaryl sulfonate having a Molecular Weight of from about 900 to 1100, the weight ratio of barium to zinc in the 2-ethylhexanoates is about 10 to 1, and the weight ratio of the ether, sulfonate and carboxylates is from about 1 to 2 parts ether and 1 to 2 parts sulfonate per part total carboxylates.

6. The composition of claim 5 wherein the monomethyl ether of ethylene glycol is substituted for 1-methoxy-2-propanol.

7. A liquid fuel composition having reduced smoking characteristics comprising a major proportion of a liquid hydrocarbon fuel and a minor proportion of a Group IIA metal salt of an alcanoic acid branched in the alpha position, a Group IIB metal salt of an alcanoic acid branched in the alpha position, an alkyl ether of a glycol having about three to 10 carbon atoms and a Group IIA metal sulfonate, wherein the weight ratio of Group IIA metal to Group IIB metal in the alkanoates is from about 5 to 1 to about 30 to 1 and the weight

proportions of total alkanoates and ether to sulfonate is about 1 to 3 parts of total alkanoates and about 1 to 2 parts of ether to 1 to 2 parts of sulfonate.

8. The composition of claim 7 wherein the fuel is a diesel fuel, the total weight of Group IIA and Group IIB metal salts of alcanoic acid is from about 0.05 to 5 percent by weight, the ether is present in amounts from about 0.05 to 5 percent by weight, the metal sulfonate is present in amounts from about 0.05 to 1 percent by weight, and wherein the weight percentages are based upon the total weight of the diesel fuel mixture.

9. The composition of claim 8 wherein the Group IIA metal alcanoic acid salt is a barium salt, the Group IIB metal alcanoic acid salt is a zinc salt, and the Group IIA metal sulfonate is a barium hydrocarbyl sulfonate.

10. The composition of claim 9 wherein the alkanoates each have from about four to 12 carbon atoms, and the sulfonate is a barium alkaryl sulfonate.

11. The composition of claim 10 wherein the total weight of barium and zinc alkanoates is from about 0.1 to 0.6 percent by weight, the glycol ether is present in amounts from about 0.2 to 0.5 percent by weight, the sulfonate is present in amounts from about 0.2 to 0.5 percent by weight, and the weight ratio of barium to zinc in the alkanoates is from about 8:1 to 12:1.

12. The composition of claim 11 wherein the Group IIA metal alkanoate is barium 2-ethylhexanoate, the Group IIB metal alkanoate is zinc 2-ethylhexanoate, the ether is 1-methoxy-2-propanol, the sulfonate is a barium alkaryl sulfonate having a Molecular Weight of from about 900 to 1100, and the weight ratio of barium to zinc in the 2-ethylhexanoates is about 10:1.

13. In the method of operating an internal combustion engine wherein a liquid hydrocarbon fuel is passed through a fuel supply system into a combustion chamber of said engine and said fuel is caused to ignite therein, the improvement comprising operating said engine on a hydrocarbon fuel containing a minor proportion of a Group IIA metal salt of an alcanoic acid branched in the alpha position, a Group IIB metal salt of an alcanoic acid branched in the alpha position, an alkyl ether of a glycol having about 3 to 10 carbon atoms and a Group IIA metal sulfonate, wherein the weight ratio of Group IIA metal to Group IIB metal in the alkanoates is from about 5 to 1 to about 30 to 1 and the weight proportions of total alkanoates and ether to sulfonate is about 1 to 3 parts of total alkanoates and about 1 to 2 parts of ether to 1 to 2 parts of sulfonate.

14. In the method of operating a compression ignition engine wherein a diesel fuel is passed through a fuel supply system into a combustion chamber of said engine and said fuel is caused to ignite therein, the improvement comprising operating said engine on a diesel fuel containing a barium and a zinc alkanoate, wherein each alkanoate is branched in the alpha position, an alkyl ether of a glycol having about three to 10 carbon atoms and a barium hydrocarbyl sulfonate wherein the total weight of said alkanoates are from about 0.05 to 5 percent by weight, said ether is present in amounts from about 0.05 to 5 percent by weight, and said sulfonate is present in amounts from 0.05 to 1 percent by weight, and the weight percentages are based on the total weight of fuel mixture.

15. The method of claim 14 wherein said fuel mixture is a diesel fuel containing barium 2-ethylhexanoate, zinc 2-ethylhexanoate, 1-methoxy-2-propanol, and a barium alkaryl sulfonate having a Molecular Weight of about 1000, wherein the weight ratio of barium to zinc in the 2-ethylhexanoates is about 10:1, the total weight of the alkanoates is from about 0.1 to 0.6 percent by weight, said ether is present in amounts from about 0.2 to 0.5 percent by weight, and said sulfonate is present in amounts from about 0.2 to 0.5 percent by weight, based on the total weight of diesel fuel mixture.
